UNITED STATES PATENT OFFICE

DANIEL BAKER DIMICK, OF BIRMINGHAM, ALABAMA

APPARATUS FOR CASTING SPIRAL CORRUGATED PIPE

Application filed July 11, 1928. Serial No. 291,909.

The present invention relates to improvements in apparatus for casting metal pipe as described in U. S. Patent #1,544,057 granted to me June 30, 1925.

5 The present invention constitutes certain improvements over my following prior patents: No. 1,544,062, granted June 30, 1925; No. 1,544,056, granted June 30, 1925; No. 1,544,058, granted June 30, 1925; No. 10 1,544,059, granted June 30, 1925; No. 1,544,060, granted June 30, 1925; No. 1,544,061, granted June 30, 1925; No. 1,550,514, granted August 18, 1925; No. 1,213,760, granted January 23, 1917.

15 It is an object of the present invention to produce a compact, efficient and reliable machine for accomplishing in a commercial way corrugated cast metal pipe, wherein the article may be cheaply produced in large quantities and with a minimum of labor.

20 Other objects of the invention consist in improving the method of applying and removing the pattern, of moving the drawing machine from one molding table to the other, 25 and of conducting the other steps and processes of the method by which the corrugated cast metal pipe is secured.

With the foregoing and other objects in view, the invention will be more fully described hereinafter, and will be more particularly pointed out in the claims appended hereto.

30 In the drawings, wherein like symbols refer to like or corresponding parts throughout the several views,

Figure 1 is a front elevation, with part shown in section, of a molding machine constructed in accordance with the present invention;

40 Figure 2 is a side view of the same with the mold in place and the pattern shown held above the mold;

Figure 3 is also a side view on an enlarged scale, with part shown in section;

45 Figure 4 is a plan view taken on enlarged scale, of the drive shaft arrangement;

Fig. 5 is an end view of the shaft taken from the right in Figure 4; and,

50 Figure 6 is a longitudinal vertical section taken through the lower portion of the ma-

chine showing the device for shifting the carriage from one molding table to the other.

Referring more particularly to the drawings, in Figure 1 two spaced rotary molding tables 7 and 8 are shown as mounted upon appropriate pedestals. The carriage 9 is shown as positioned in back of one of the tables 7. This carriage 9, as shown in Figures 2 and 3, is adapted to slide along the beams or rails 10 and 11 for the purpose of shifting it from one table 7 to the other table 8. These tables are adapted to receive the molds shown at 12 in Figure 2. The carriage supports the corrugated cylindrical pattern 13, shown in Figure 2. As will be understood from my prior patents, this pattern 13 is adapted to be lowered into the mold 12. A sand-slinger is thereupon brought forward and sand packed thereby in the mold at inside and outside of the pattern 13. The pattern 13 is subsequently removed from the packed sand in the mold 12, leaving a spiral seamless corrugated cavity into which the molten metal is poured to cast the pipe.

55 The pattern 13 may be of the type shown in my prior patents aforesaid and it may be supported in any appropriate manner from the rotary head 15 carried by the vertically movable arm 16. The head is provided with a large gear wheel 17, shown in Figure 3 as disposed in mesh with a pinion 18. The gear wheel 17 is carried on a vertical shaft 19 and the pinion upon a shaft 20. The pinion is in mesh with a second pinion 21 keyed to rotate with a vertical drive shaft 22 but arranged to

60 slide longitudinally on the shaft 22 as becomes necessary in the vertical movement of the arm or head 16 which is counterbalanced by the counterbalance arrangement indicated generally at 23.

65 The head or arm 16 is carried by a frame 23 having upper and lower pairs of sleeves 24 and 25 positioned to slide upon the guide rods 26 and 27 which are mounted in the carriage 9. The frame 23 is also provided with central collars 28 to slide upon the drive shaft 22.

70 At the base of the drive shaft 22 there is fixed thereon a beveled pinion 29 disposed in mesh with a complementary pinion 30 on a shaft 31 shown in Figure 4. This shaft 31, 75

55

through the pinions 29 and 30 provides for the rotation of the pattern 13.

The frame 23 is shown in Figure 3 to be provided with racks 32 disposed in mesh with toothed wheels 33 mounted on a shaft 34 in the carriage 9. On this shaft 34 is also fixed a sprocket 35 engaged by an endless chain 36. The chain is trained at its lower end about the sprocket 37. This sprocket is on a shaft 38 for the worm wheel 39 shown in Figure 4.

10 The casing 40 containing the worm wheel is shown in Figure 3.

The worm wheel 39 as shown in Figure 4, is disposed in mesh with a worm 41 on a worm drive shaft 42. This drive shaft 42 is provided with a fixed gear wheel 43 in mesh with a pinion 44 fixed on a shaft 45. The shaft 45 contains loosely thereon the pinion 46 and the gear wheel 47, the pinion and gear wheel respectively having the clutch sections 48 and 49 with a complementary axially slidable splined clutch collar 50 therebetween adapted to engage one clutch member while disengaging the other or to be moved to a neutral position between the two.

25 The shaft 45 is in axial alignment with the shaft 31 and complementary clutch members 51 and 52 are mounted upon the adjacent ends of these shafts. These clutch elements are fixed to rotate with the shafts but the clutch element 52 is slidably axially to admit of its being shifted into and out of engagement with its complementary clutch member 51. A yoke and handle 53 connect the sliding clutch collars 50 and 52 to enable the simultaneous operation thereof.

30 The pinion 46 is disposed in mesh with a gear wheel 54 fixed on a shaft 55. The gear wheel 47 is disposed in mesh with a pinion 56 fixed on the shaft 55. This shaft 55 is provided with a sprocket 57 engaged by the drive chain 58. Such chain is driven by the reversible electric or by other motor 59, shown in Figure 3. This motor and the gearing referred to are mounted in appropriate bearings and supports within the hollow carriage 9.

35 In Figure 3 a shaft 60 is shown extending in axial alignment with the shaft 55 and having a clutch 61 adapted to couple the shaft 60 to the drive shaft 55. The shaft 60 is provided with a sprocket wheel 62 engaged by the chain 63 which extends downwardly through the bottom portion of the carriage 55 and drives a sprocket 64 on the shaft 65. This shaft 65 carries a bevel gear wheel 66 in mesh with a similar bevel pinion 67. This latter bevel gear is provided with a central nut 68 threaded to engage the threads upon the 40 screw feed shaft 69. The pinion 67 and nut are mounted between the two thrust bearings 70 and 71, shown in Figure 6, which depend from the base of the carriage 9. The screw feed shaft 69 is mounted through appropriate 45 bearings 72 and 73 upon the bed or founda-

tion and this shaft extends loosely through the bearings 72 and 73 and outwardly therebeyond. The terminal portions of the shaft are encircled by coil springs 74 and 75 which abut at their inner ends against the bearings 70 and at their outer ends against washers or heads 76 and 77 fixed to the screw feed shaft whereby to cushion the longitudinal thrust of the same and the movement of the carriage.

75 As shown in Figure 1 the turn tables are provided with internal gears 78 in mesh with pinion 79 upon the upper ends of the vertical shafts 80 and 81. These shafts carry bevel pinions 82 and 83 in mesh respectively with bevel pinions 84 and 85 upon axially aligned shafts 86. These shafts carry the bevel gear wheels 87 engaging with the pinions 88 upon the drive shafts 89 provided with a clutch mechanism 90.

80 By shifting the clutch mechanism 90 back and forth one or the other turn tables 7 or 8 may be made to rotate. Any other mechanism for rotating the turn tables may be supplied and the shafts may be driven by electric or other motor.

85 In operation, a flask is placed on one of the turn tables 7 or 8, such for instance as the flask 12 upon the turn table 8 shown in Figure 2. The turn table is secured in any appropriate manner against rotary motion. The pattern 13 is secured to the turning head 15 and the carriage is moved to a position where the pattern 13 is directly above the flask 12.

90 The carriage is made to move on the tracks 10 and 11 by engaging the clutch 61 whereby the rotation of the drive shaft 55 will be imparted to the shaft 60, shown in Figure 3. By virtue of the chain 63 and connected sprockets, the pinion shaft 65 is rotated thus communicating motion to the bevel pinion 67, advancing it along the feed screw 69, and by reason of the end thrust bearings 70 and 71, requiring that the carriage 9 partake of the same motion in a direction longitudinally of the feed screw 69. Sudden shocks in starting and stopping are absorbed through the compression spiral springs 74 and 75.

105 During this longitudinal travel of the carriage 9, the clutches 50 and 52 in Figure 4 may be disengaged. However, on arriving at the correct position, it becomes necessary to lower the pattern 13 into the flask 12. This may be done at "high speed" by engaging the clutch 50 with the clutch element 48 of the loose pinion 46 driven by the large gear wheel 54. This arrangement of gearing requires that the shaft 45 turn many times faster than its driver 55 and a "high speed" of rotation is communicated through the gear wheels 44 and 43 to the worm shaft 42. The driving of the worm wheel 39 correspondingly drives the chain 36 and the toothed wheels 33 which

mesh with the racks 32 shown in Figure 3. The electric motor 59, which is reversible, is driven in the proper direction to secure the lowering of the pattern 13. The pattern 13 is not rotated during this lowering movement 5 and it is lowered rapidly. The final setting of the pattern may be in "low speed". This "low speed" condition is secured by shifting the clutch 50 into engagement with the clutch element 49 of the loose gear wheel 47 meshing with the small pinion on the drive shaft 55. Through this ratio a much slower movement will be imparted to the intermediate 45 and consequently the worm shaft 42 will be driven slowly. The pattern 13 will also be given a rotary motion due to the engagement 15 of the clutch collar 52 with the clutch element 51. The pattern is then disconnected from the head 15 and the carriage moved out of the way. Another pattern may be secured 20 in the head and shifted to the other table whereupon a similar operation takes place. The turn table 8 is then permitted to rotate while tempered molding sand is rammed between the pattern and cheek and also between 25 the pattern and arbor. The excess sand is removed and the mold is in condition to have the pattern 13 removed. The arm 16 is then brought over the pattern and is lowered in "low speed" as above referred to. The head 30 15 is engaged with the pattern 13 and the motor 59 is reversed. This reverse movement is still continued in "low speed" and the pattern 13 is rotated 35 while at the same time the arm 16 is lifted, the clutches 50 and 52 being engaged. The turn table 8 is of course secured against 40 rotary motion. The pattern 13 is subjected to a combined rotary and lifting motion synchronized to the lead of the pattern corrugations. The pattern is thus removed 45 from the mold without destroying the mold cavity which is seamless in a cylindrical sense and enables the casting in one piece of the spiral corrugated pipe, the mold 12 being removed to the casting floor for this purpose. The pattern after removal is ready for insertion in another mold undergoing preparation.

50 It will be seen that in the present apparatus, the pattern may be quickly raised and lowered with the machine in "high speed" without the turning of the pattern. The pattern may also be raised and lowered 55 slowly while it is subjected to rotary motion, the two being so timed that the vertical drive of the pattern is exactly duplicated by means of the racks and rack gears.

It will be understood that the machine may 60 be utilized in connection with a single mold turn table or with two or more turn tables.

The carriage is provided with locking dogs 95 mounted to reciprocate in guide sleeves 96 and having handles 97. Recesses 98 are 65 provided in the foundation or track for re-

ceiving the locking dogs 95 at opposite ends of the movement of the carriage whereby to align the axis of the pattern with the axis of the mold or flask. These dogs may be withdrawn, by hand before the carriage can be again put into movement. 70

It will be obvious that many changes in the construction, combination and arrangement of parts could be made, which could be used without departing from the spirit of my invention, and I do not mean to limit the invention to such details, except as particularly pointed out in the claims. 75

Having thus described my invention, what I claim and desire to secure by Letters Patent of the United States is:— 80

1. An apparatus for molding spiral corrugated metal pipe comprising a holder for a flask, a rotary and reciprocating support for a pattern, and means for rapidly raising and lowering said support without rotation of the pattern and for more slowly raising and lowering the support with rotation of the pattern. 85

2. An apparatus for molding spiral corrugated metal pipe comprising a reciprocating and rotating support for a pattern, and means whereby said support may be reciprocated at "high speed" without entailing rotation of the pattern and whereby also the support may be reciprocated more slowly but with turning of the pattern. 95

3. An apparatus for molding spiral corrugated metal pipe comprising a support for a pattern having a vertical sliding movement and a movement of rotation, a motor, and connections between said motor and support for shifting the support back and forth either with or without rotation of the pattern. 100

4. An apparatus for molding spiral corrugated metal pipe comprising a support for a pattern mounted for vertical shifting movement and for horizontal rotary movement, a motor, and connections between said motor and the support for raising and lowering the pattern at "slow speed" while turning the pattern and at "high speed" without turning the pattern. 105

5. An apparatus for molding spiral corrugated metal pipe comprising a carriage, a vertically shiftable frame on the carriage, a rotary head in the frame for supporting a pattern, and means supported by the carriage for raising and lowering said frame either rapidly or slowly and for rotating said head and pattern simultaneously with the slower movement of the frame. 110

6. An apparatus for molding spiral corrugated metal pipe comprising a carriage, a frame mounted for movement therein, a rotary head carried by the frame for supporting a pattern, a motor supported by the carriage, connections between said motor, frame and head for raising and lowering the frame rapidly. 125

idly without rotation of the head and for raising and lowering the frame slowly with rotation of the head, and means for shifting the carriage.

7. An apparatus for molding spiral corrugated metal pipe comprising a carriage, a shiftable frame therein, a rotary head in the frame, a shaft for driving the rotary head, connections for shifting the frame, and a motor for driving said connections at "high speed" without driving the shaft and at "low speed" with driving of said shaft.

8. An apparatus for molding spiral corrugated metal pipe comprising a carriage, a shiftable frame therein, a rotary head in the frame for supporting a pattern, a drive shaft for the rotary head, connections for shifting said frame, a motor, and a selective means whereby the motor may drive the connections at "high speed" without driving the shaft or alternately may drive the connections at "low speed" with simultaneous driving of the shaft.

9. An apparatus for molding spiral corrugated metal pipe comprising a carriage, a shiftable frame therein, a rotary head on the frame, a drive shaft for the head with which the frame has sliding movement, a rack on the frame, a drive wheel for meshing with the rack, a motor, and means whereby the motor may drive the wheel at rapid or "slow speeds" and may drive the shaft only when driving the wheel at "low speed".

10. An apparatus for molding spiral corrugated metal pipe comprising a carriage, a shiftable frame therein, a rotary head on the frame for carrying the pattern, a motor, a drive shaft driven by the motor, a transmission shaft, high and low selective speed transmission elements between said shafts for driving the transmission shaft, a worm shaft positively driven by said transmission shaft, a worm wheel connection for driving said frame, a drive shaft for the rotary head, and means whereby said drive shaft may be driven from the transmission shaft whenever the latter is rotated in "slow speed".

11. An apparatus for molding spiral corrugated metal pipe comprising a shiftable carriage, a rotary and reciprocating support for a pattern in the carriage, a motor in the carriage for driving said support, and connections whereby said motor may shift the carriage.

12. An apparatus for molding spiral corrugated metal pipe comprising a shiftable carriage, a shiftable and rotary support for a pattern therein, a motor in the carriage for driving and rotating the support, a feed screw below the carriage, a travelling nut gear on the feed screw arranged to move the carriage, and connections between said motor and the nut gear for rotating the latter.

13. An apparatus for molding spiral corrugated metal pipe comprising a shiftable

carriage, a shiftable and rotary head thereon for supporting a pattern, a motor in the carriage for driving and rotating the head, a shaft adapted to be driven by the motor, a pinion shaft driven from said first mentioned shaft and carried by the lower portion of the carriage, a pinion on said shaft, a nut gear meshing with said pinion, thrust members on the carriage extending on opposite sides of said nut gear, a feed screw supported beneath the carriage and engaging said nut gear, and means for resiliently supporting the ends of said feed screw.

14. An apparatus for molding spiral corrugated metal pipe comprising a carriage, a movable pattern carrying frame on the carriage, a track on which the carriage is mounted for movement, a plurality of mold tables adjoining the track, and locking means between the carriage and track for arresting the carriage and holding it immovable at the mold tables and for aligning the pattern with the mold.
